LAPPING APPARATUS AND METHOD

David A. Wallace, Detroit, Mich., assignor to
 Chrysler Corporation, Highland Park, Mich., a
 corporation of Delaware

Application June 6, 1938, Serial No. 212,050

9 Claims. (Cl. 51—59)

This invention relates to improved lapping apparatus and method and is a further development of the invention set forth in my co-pending application, Serial No. 107,377, filed October 5 24, 1936.

More particularly, the invention pertains to improvements in the feeding mechanism by which the pressure with which the lapping elements are urged against the work is varied during the lapping cycle.

One of the important factors involved in efficient lapping of surfaces is the lapping pressure applied between the work and the lapping elements. If the optimum unit lapping pressure, which varies with different materials and in some cases at different stages of the lapping operation, are substantially maintained or closely approached throughout the lapping operation, surfaces may be finished to a completely lapped state in much shorter time and with less relative lapping movements between the work and lapping elements than required when incorrect lapping pressures are applied. Since the area of contact between an unlapped surface and lapping elements increases as the roughness of such surface is decreased during lapping thereof, the employment of a uniform force of application between the lapping element and the work results in a decreasing unit lapping pressure as the lapping operation progresses.

It is one of the main objects of this invention to compensate in the force of application between the work and lapping elements for the increase in contact therebetween so as to maintain predetermined unit lapping pressures throughout the entire cycle of the lapping operation.

Another object of the invention resides in the provision of an improved lapping apparatus by which the pressure with which a lapping element is urged against a piece of work may be brought to different predetermined values at diverse stages of a lapping cycle and without interrupting the lapping operation.

Other objects of the invention are to provide a lapping apparatus of this character in which the lapping pressure applied between the lapping element and the work varies in a predetermined relationship with respect to a relative movement between the work and the tool; to provide means in apparatus of this kind for increasing the lapping pressure periodically after the lapping operation has continued throughout predetermined numbers of complete lapping movements or throughout a predetermined time in-

interval; and to provide means of this character in lapping apparatus which may progressively increase the lapping pressure at a predetermined rate as the lapping operation progresses from one stage to a more advanced stage.

Further objects of the invention are to provide a lapping apparatus of this kind by which the lapping element, while reciprocating at a relatively high speed approaching a vibratory order, is urged against a rotating piece of work 10 with increasing pressure by control mechanism responsive to a predetermined number of rotations of the work; and to provide a pivotally mounted lapping element reciprocating member having 15 relatively extensible sections including a pressure actuated device for urging the aforesaid parts apart in order to vary the force of application of the lapping element carried thereby upon the work.

Additional objects of the invention are the 20 provision of an improved lapping method in which efficient lapping is accomplished by so increasing the force of application between the lapping elements and the work as to maintain the unit lapping pressure within a predetermined 25 range of values during increasing of the area of contact between the work and lapping element; and to provide a method of this kind which is particularly adapted for use in connection with lapping apparatus of the type which has reciprocating lapping elements for operating upon a rotating piece of work.

Other objects and advantages of the invention will be more apparent from the following description taken in connection with the accompanying drawing, in which:

Fig. 1 is a side elevational view, partly in section, of lapping apparatus embodying the invention.

Fig. 2 is an enlarged, fragmentary, horizontal 40 sectional view taken on the line 2—2 of Fig. 1 and showing the right end portion of the lapping apparatus.

Fig. 3 is a transverse sectional view taken as indicated by the line 3—3 of Fig. 2.

Fig. 4 is a transverse, sectional view taken on the line 4—4 of Fig. 2.

Fig. 5 is a side elevational view of a cam which may be used in place of the cam shown in Fig. 2.

In the form of the invention illustrated in the 50 drawing, the lapping apparatus, generally designated by the numeral 10, comprises a shank portion 11, having spaced bearing recesses 12 and provided with cooperating bearing caps 13 for revolvably mounting the tool on a pair of crank- 55

throw bearings 14 of master crankshafts 15 and 16 which are rotatably mounted in a machine bed structure (not shown).

5 A lever 17 is pivotally mounted at a location intermediate its end on the shank portion 11 of the tool 10 by a bolt 18 as illustrated in Fig. 1. The lever 17 is provided with an end portion 19 on which a tool head 20 is axially slidably mounted. The tool head 20 has a clearance slot 10 for the bolt 18 and also has a pair of H-shaped cross-sectional portions 21, one of which is best shown in Fig. 4, which are guided on the end portion 19 of the lever, and held against removal from the latter by a pin 22 extending through a 15 slot 23 formed in the intermediate portion of the lever 17. The elongated slot 23 accommodates limited relative axial movement of the tool head 20 with respect to the lever 17. Formed in the end portion of the lever 17, opposite from the end 20 portion 19 thereof is a cylindrical bore 19' in which is disposed a piston 24 which is secured by the pin 22 to the tool head 20. The piston 24 is urged to the left, as viewed in Fig. 1, by a spring 26 bearing against the end wall of the end of 25 the cylindrical bore 19'. The left end of the bore 19' is suitably closed by a plug 27 and a sealing member 28 to provide a pressure tight cylinder which has a flexible conduit 30 leading thereto for admitting fluid pressure to cause the 30 piston 24 to overcome the action of the spring 26, thereby urging the tool head 20 rightwardly as viewed in Fig. 1.

The outer end portion of the tool head 20 is provided with a channel shaped recess 31 having a side wall 32 formed integral with the tool head and a detachable side wall, or flange 33, removably mounted on the tool head 20 by bolts 34. The side walls 32 and 33 of the recess 31 are provided with inwardly extending trunnions 35 on 40 which alapping member 36 is mounted. Thelapping member 36 comprises a block 37 having recesses 38 therein in which are securely mountedlapping elements 39 comprising natural stone, artificial compressed stone or other abrasive or 45lapping material. Thelapping member 36 may be conveniently installed and removed from the tool head 20 by removal of the plate 33, the right end of which constitutes one wall of the recess 31. A pair of spring-loaded detent members 40 50 act on respectively opposite sides of the right end portion 19 of the lever 17 to yieldably maintain the tool head 20 in its central position.

Formed in the left extremity of the lever 17 is an elongated slot 45 having its maximum dimension extending in the direction of the axis provided by the bolt 18. The slot 45 accommodates a pin 46 eccentrically located on the lower extremity of a shaft 47 of a motor 48, mounted on the shank portion 11 of the tool. The motor shaft 47 is rotatably journaled in spaced bearing members 49 and 50 carried by the shank 11 of the tool. The eccentrically located pin 46 of the motor shaft 47 has an external surface of generally spherical curvature which is adapted to 60 operate upon the side walls of the elongated slot 45, during operation of the motor, in such a manner as to oscillate the lever 17 about the axis provided by the bolt 18.

70 During operation of thelapping tool, the motor 48 is preferably operated at a speed sufficiently high to cause oscillatory movement of the lever 17 throughout a relatively short stroke and at a comparatively high speed approaching that of a vibratory order. The lever 17 in turn recip-

rocates thelapping member 36 and thelapping elements 39 at a correspondingly high speed.

The work comprises a crankshaft 51, to which thelapping elements 39 are applied, which is preferably rotatively mounted with respect to an axis extending in a direction generally normal to the axis of oscillatory movement of the lever 17. The crankshafts 51, 15 and 16 are drivingly rotated in synchronism with each other as by a motor 52 having a pinion 53 meshed with a gear 54 detachably and non-rotatably secured to the work crankshaft 51. The crankshaft 16 carries a gear 55 drivingly engaged with an idler gear 56 which also meshes with the gear 54.

Thelapping elements 39 may be variably yieldably urged against the work by the admission of fluid pressure medium to the cylinder 19' through the inlet conduit 30 under the control of valve mechanism, generally designated by the numeral 64 in Fig. 1. The valve mechanism 64 may be operated in any desired manner to automatically vary the force with which thelapping elements are applied to the work. In the illustration shown, this valve mechanism is operated in timed relationship to one of the relativelapping movements of the work and thelapping elements.

The valve mechanism 64 includes a casing 65 having a low pressure chamber 66 and a high pressure chamber 67 communicatively connected by a passage 68 in which a variable valve 69 is mounted. The valve 69 has a tapering groove 70 therein and it is normally urged leftwardly, as viewed in Fig. 1, toward its closed position by a spring 71. Fluid pressure medium is fed under pressure into the high pressure chamber 67 by 35 a pump 72 which draws fluid medium from a tank 73. When the valve 69 is opened, by-passing of fluid from the chamber 67 to the low pressure chamber 66 is accommodated and a corresponding reduction is produced in the pressure in the high pressure chamber 67 and in the cylinder 19' of thelapping element urging apparatus. By-passed fluid is returned from the low pressure chamber to the tank 73 through an outlet tube 74.

The valve 69 may be automatically actuated in any desired manner so as to vary the fluid pressure by which thelapping elements are urged against the work at predetermined intervals. In the form shown, this is accomplished by providing the valve 69 with a stem 75 having an end portion projecting externally of the casing 64 and carrying a cam following roller 76 which abuts against a cam 63. The cam 63 is non-rotatably fixed to a worm gear 61 having teeth 55 meshed with a worm 60 that is driven by a shaft 58 and pinion 59. The pinion 59 is in turn driven by a gear 57 non-rotatably fixed to one of the main bearings of the master crankshaft 15, as illustrated in Fig. 1.

The speed ratio reducing effect of the gearing may be predetermined to cause the cam 63 to complete one rotation in any desiredlapping period which is preferably commenced while the valve 69 is fully open so as to gradually close the valve as thelapping cycle progresses, thereby gradually increasing the force applied by the fluid medium and piston 24 in urging thelapping elements against the work. If desired, the cam 63 may be so contoured as to increase the force by 60 which thelapping elements are urged against the work at a rate such that the tendency of the unitlapping pressure to decrease by reason of the increase in contacting area between thelapping element and the work, will be compensated.

ated for, thus enabling the unit lapping pressure to be maintained substantially constant during the entire lapping operation.

A cam of the general contour illustrated in Fig. 4 may be employed when it is desired to increase the lapping pressure in steps. This cam has a plurality of successive dwells 16 which are progressively spaced at further distances from the axis of the cam. Excellent results can be obtained, for example, by so constructing a cam like that shown in Fig. 5 and its driving mechanisms as to apply a twenty pound pressure for the first five minutes of the lapping operation, a thirty pound pressure during the next five minutes, a forty pound pressure during the next five minutes, a sixty pound pressure during the next eight minutes and a one-hundred pound pressure during the last seven minutes of the lapping cycle. The lengths and numbers of diverse pressure periods may be predetermined over substantially large ranges.

The time required to lap a piece of work is materially shortened by employment of the improved lapping apparatus and method. An optimum unit lapping pressure may be maintained throughout all stages of a lapping cycle even though the contacting area of the lapping element and work surface increases by reason of the removal of irregularities from the surface of the work as the lapping operation progresses.

Although but several specific embodiments of the invention are herein shown and described, it will be understood that various changes in the size, shape and arrangement of parts may be made without departing from the spirit of the invention.

What is claimed:

1. Surface finishing apparatus including a support for a piece of work, a tool having an abrading element engageable with said work, means for producing relative abrading movements including a relative rotative movement component between said work and said element, and mechanism for urging said abrading element and work together including means operable in timed relationship with respect to said relative rotative movement component of said abrading movements for increasing the force by which said element and work are urged together from one value to a higher value without an accompanying intermediate decrease in said force during the progress of a finishing operation.

2. Lapping apparatus including a support for a piece of work, a lapping tool having a lapping element engageable with a surface of said work, means for rotating said work, and mechanism for holding said lapping element and work in contacting relationship with a predetermined force during the initial stages of a lapping operation including means operable in timed relationship to rotation of said work for progressively increasing said force as said lapping operation continues.

3. Surface finishing apparatus including a support for a piece of work, a tool having an abrading element engageable with said work, means for producing relative movements between said work and said element, and mechanism for yieldably holding said lapping element and work in contacting relationship including a resilient member and means operating upon said resilient member for urging said element and said work together with a predetermined force during the initial stage of a lapping operation and including control apparatus for said means adapted

to increase said force at a subsequent stage of said lapping operation.

4. Surface finishing apparatus including a support for a piece of work, a tool having an abrading element engageable with said work, means for producing relative movements between said work and said element, and mechanism for yieldably holding said lapping element and work in contacting relationship including a resilient element and means for operating upon said resilient element with a predetermined force during the initial stage of a lapping operation and including variable control apparatus for said means adapted to intermittently increase said force at successive subsequent stages of said lapping operation.

5. Surface finishing apparatus including a support, means on said support for rotatably supporting and drivingly rotating a piece of work, a tool fixture, an abrading tool having a main body portion movably mounted on said fixture and an abrading element carrier shiftably mounted on said main body portion for movement toward and away from said work, an abrading element mounted on said carrier, means for moving said main body portion of said tool to produce abrading movements of said element, fluid pressure responsive mechanism mounted on said main body portion of said tool and operating upon said carrier for variably urging said element against said work, and a fluid pressure system connected with said mechanism including control means operable in timed relation with respect to rotation of said work for varying the pressure with which said element is urged against said work during operation of said apparatus.

6. Surface finishing apparatus including a support, means on said support for rotatably supporting and drivingly rotating a piece of work, a tool fixture, an abrading tool having a main body portion movably mounted on said fixture and an abrading element carrier shiftably mounted on said main body portion for movement toward and away from said work, an abrading element mounted on said carrier, means for moving said main body portion of said tool to produce abrading movements of said element, fluid pressure responsive mechanism mounted on said main body portion of said tool and operating upon said carrier for variably urging said element against said work, and a fluid pressure system connected with said mechanism including valve mechanism and control means so constructed and arranged as to progressively increase the force with which said element is urged against said work at predetermined intervals during an abrading operation.

7. The method of lapping a piece of work which comprises applying with a predetermined force a lapping element to a surface of a piece of work to establish a predetermined unit lapping pressure during initial lapping of said surface, producing relative lapping movements including a relative rotative component movement between said lapping element and said surface, and gradually increasing said force at a rate proportional and in timed relationship to the number of said relative rotative component movements.

8. Lapping apparatus including means for rotatably supporting a piece of work, means for rotating said work, a fixture including means for reciprocably holding a lapping element in engagement with a surface of said work, driving means carried by said fixture for reciprocating

said lapping element during rotation of said work, and means for varying the lapping pressure in response to a predetermined number of rotations of said work.

- 5 9. Crankshaft lapping apparatus including a machine bed structure, means thereon for rotatively supporting a crankshaft to be lapped on its normal axis, a pair of master crankshafts rotatively mounted by said means about axes 10 substantially parallel to said normal axis and

each being substantially identical in crank throw arrangement to said crankshaft to be lapped, means for driving said work crankshafts in synchronism with each other, a lapping tool supported by said first means having a lapping element adapted for engagement with the crank throw bearing of said work crankshaft, and means for varying the lapping pressure in response to movement of said master crankshafts.

DAVID A. WALLACE.
